UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL STOVE.

Application filed April 19, 1920. Serial No. 374,827.

To all whom it may concern:

Be it known that I, RUDOLPH HOFFMAN, a citizen of the United States, residing at Kankakee, in the county of Kankakee and State of Illinois, have invented certain new and useful Improvements in Oil Stoves, of which the following is a specification.

The invention relates to oil stoves having burners of the constant-level type, in which 10 the burner proper comprises a burner bowl provided with raising and lowering means operable to vary the position of the burner with reference to a certain level at which a supply of oil is maintained, the bowl 15 being connected by a suitable pipe connection with a source of oil supply.

The invention has especial reference to oil stoves of the character indicated in which the pipe connection between the burner bowl and the source of oil supply is of 20 such a character as to permit of the raising and lowering of the burner; and an important object of the invention is to provide an improved form of connection which 25 is of a flexible nature and which offers a minimum amount of resistance to the up and down movements of the burner.

In prior burners, of the constant-level type, which have embodied a flexible connection between the burner and the source of oil supply, the connections have been in the form of a flexible pipe extending in a generally horizontal direction directly from the burner bowl. With this arrangement 30 it has been found that when the burner is suddenly lowered an objectionable flaring up of the flame has occurred, owing to the rush of oil under the action of gravity to the burner bowl and hence causing the generation of an excessive amount of vapor. An 35 important object of the present invention is to overcome this objection, and this is accomplished by arranging the oil conducting means for the burner so that the portion 40 of such means communicating with the burner shall depend vertically a substantial distance from the burner so as to eliminate the action of gravity upon the oil in a manner to cause an excessive flow thereof to 45 the burner.

A further object of the invention is to provide a connection between the burner bowl and its source of supply in which pro-

vision is made for the collection of sediment and the like so as to insure the efficient 55 operation of the burner.

A further object of the invention is to provide improved means for mounting the burner for up-and-down movement.

Still another object of the invention is 60 to provide improved means for indicating the proper position of the burner with reference to the constant oil level.

In the accompanying drawings, wherein I have illustrated a preferred form of my 65 invention, Figure 1 is a side elevation partially in section of the improved burner. Fig. 2 is a front elevation of the burner. Fig. 3 is a fragmentary sectional view, on an enlarged scale, through the flexible connection or conductor which permits of the vertical movements of the burner with reference to a fixed source of oil supply. Fig. 4 is a fragmentary end elevation of the 70 means shown in Fig. 3. Fig. 5 is a fragmentary detail view of a flexible metallic hose forming part of the flexible oil conductor. 75

In the drawings 7 designates generally 80 one of a series of burners supported for vertical movement beneath the top of a stove A and comprising an annular trough or bowl 8. From the bowl 8, a tubular stem 9 depends into operative relation with a support 10 embodying a tubular member or 85 sleeve 11 with which a raising and lowering device 12 is adapted to coact. From the lower end of the stem 9 a flexible conductor 13 leads in a generally horizontal direction to an oil supply pipe 14. The latter extends longitudinally of the stove and is connected by means of a pipe 15 with the well 16 of an oil supply tank or reservoir 17. By means of the device 12, the burner is adapted to be raised and lowered with reference to a constant oil level (Fig. 1) which is maintained by the reservoir 17 and its well 16 in a well known manner. 90 95

The burner 7 may be of any well known or preferred construction, comprising the 100 burner bowl 8 adapted to receive an annular lighting ring (not shown) and to support a chimney 18.

The stem 9 which depends from the trough 8 is rigidly secured to the trough at 105 the lower edge thereof, as by brazing; so

as to provide a communication between the trough and the source of oil supply. The stem is made of substantial length and at its lower end enters a fitting 19 arranged for 5 vertical movement within the support 10.

The support 10 comprises a bracket 20 of inverted U-shape having a front wall 21 and provided with ears 22 by means of which the bracket is rigidly supported upon a longitudinal portion of the stove frame A. Rigid with the top portion of the bracket is the member or sleeve 11 which is vertically disposed and adapted to neatly receive the stem 9 so as to guide the latter in its up and 15 down movements.

For the purpose of enabling the raising and lowering device 12 to coact with the sleeve 11 and the stem 9, the sleeve is externally threaded as at 23 and the stem is provided with a fixed collar 24. Said device 12 has an internally threaded member or nut 25 engaging with the screw threads 23 and having a pair of upstanding arms 26 shaped at their upper ends to engage with the member 24 which at its upper peripheral edge is provided with an annular rim or flange 27. The upper ends of the arms 26 are bent to form fingers 28 adapted to slidably engage with said flange 27 and at the upper ends of 25 the arms, shoulders 29 are provided to engage with the underside of the member 24. The nut 25 carries a plurality of arms 30 (herein three in number), each of which carry a radially extending handle 31. It 35 will be seen that by the rotation of the member or nut 25 the raising or lowering of the burner is effected.

The flexible pipe connection 13 between the lower end of the stem 9 and the feed 40 pipe 14 may comprise a metallic conductor 32 consisting of a plurality of relatively movable but nonslidable sections 33 arranged in two series near opposite ends of the conductor, and portions 34 in the form 45 of rigid pipes connecting said series with each other and with the fitting 19. It will be obvious that the two series of relatively movable sections form in effect a pair of bellows-diaphragms which permit the bending 50 of the conductor reversely adjacent its opposite ends in the up and down movement of the burner. As shown in Fig. 3 said diaphragms are formed from sheet metal of such character as to be readily flexible. 55 Centrally of the diaphragms and coaxially of the conductor are provided openings 35 by means of which the diaphragms communicate with each other and with the connecting portions 34 therebetween. At one 60 end said conductor enters the fitting 19, an end portion 34 of the conductor being suitably secured in the fitting; and at the other end the conductor is secured upon a fitting 36 which communicates with the feed pipe 14. In this latter instance the rearmost dia-

phragm section 33 is shaped to provide an annular nipple 37 arranged to fit over the end of the fitting 36, the nipple being rigidly secured in place by suitable means as by soldering.

The flexible connection 13 may also comprise an inner conductor 38 entered within the conductor 32 and secured at its opposite ends in the fittings 19 and 36. This inner conductor is preferably formed from flexible metallic tubing embodying a plurality of sections 38^a having interfitting relatively slidable portions provided with a suitable packing 38^b between the sections. The function of this inner conductor is to prevent the collection of sediment in the diaphragms 33, while permitting of the easy bending of the connection as a whole, offering no material resistance to the bending of the outer conductor 32. The inner conductor while capable of use, especially in some instances, independently of the outer conductor, is preferably used in conjunction with the latter which forms an absolutely tight closure for the inner conductor. It will be seen that the construction provided forms a flexible connection of a highly efficient character.

The feed pipe 14 is stationarily mounted in any suitable manner in the stove frame A and carries upon its upper side the fittings 36 from which the flexible connections 13 lead to the several burners of the stove. As shown in Fig. 3, the fittings may be mounted upon the pipe 14 by means of a nipple 39 screw-threaded into the pipe and entered through a seat or cup member 40 which is provided in its bottom with a packing washer 41 upon which the lower end of the fitting 36 is adapted to rest. The fitting is clamped in position in the cup member 40 by means comprising a clamping member 42 surrounding the pipe and a screw 43 engaging with the fitting 36 and with a nut 44 engaging the clamping member 42.

For the purpose of permitting the removal of sediment from the pipe connection between the feed pipe 14 and the burner 7, I preferably provide in the fitting 19 a sump 45 having a removable screw plug 46. Preferably the plug 46 is in the form of a stem having a head 47 and a screw-threaded end portion 48 adapted to be entered through an opening 48^a provided in the lower portion of the sump and into an internally threaded boss 49 formed opposite the opening on the interior of the sump. Between the head 47 and the sump surrounding the opening 48^a may be provided a suitable packing washer 50.

For the purpose of indicating the various operative and inoperative positions of the burner, I provide an indicator comprising a pointer 51 carried by the fitting 19 (Figs. 1 and 2) and a scale formed on the front wall 22 of the bracket 20. The pointer 51 is

mounted upon a boss 52 on the fitting, as by means of a screw 53, a slot 54 being provided in the wall 21 of the bracket to receive the boss. The scale upon the wall 21 may consist of suitable legends such as "Out," "Med.," "High" and "Light," stamped upon the forward face of the wall 21.

Preferably I provide means for enclosing the flexible connections 13, to prevent the accumulation thereon of dust and dirt which might interfere with the free flexing of the diaphragms. Herein this means is in the form of a sheet metal plate 55 suitably secured in position over the diaphragms 13. Preferably the plate extends throughout the length of the stove and has at its forward end a downwardly extending flange 56 apertured to receive the forward end portion 34 of the flexible conductor 32, and secured at its lower edge upon a portion of the stove frame A which carries the bracket 20. At its rear edge the plate 55 may be secured to the frame A in any suitable way.

It will be seen that by reason of the peculiar arrangement of the various portions of the fuel conducting means, and especially of the stem 9, the supply of oil to the burner bowl 8 is effected in such a manner as to maintain the level of the oil constant, the action of gravity upon the oil tending to cause an excessive flow when the burner is lowered, and hence an abnormally great vaporization as the oil strikes the heated burner bowl, being eliminated together with the resulting objectionable flaring up of the flame.

It will be apparent that I have produced an oil stove which is of a very practical character. The burner is advantageously supported for up and down movement with the greatest facility. The flexible connection provided between the source of oil supply and the burner is of such a character as to offer no material resistance to the up and down movements of the burner in a true vertical path, and are also of a very lasting and durable character. Provision is made for the removal of sediment from the connection between the source of oil supply and the burner. And finally, the arrangement of parts is compact, and unsightly parts are concealed from view.

It is to be understood that while the invention is illustrated and described with considerable particularity, it is contemplated that various changes may be made in construction and arrangement without departing from the spirit and scope of the invention as expressed in the following claims.

I claim as my invention:

1. In an oil stove, the combination with a source of oil supply and a burner mounted for vertical relative movement, of means providing a connection between the oil supply and the burner adapted to permit of such relative vertical movement, comprising a

hollow conductor extending in a generally horizontal direction and having interposed at spaced points therein relatively movable sections adapted to render the conductor capable of flexing reversely near its opposite ends so as to permit such relative vertical movement between the burner and the source of oil supply. 70

2. In a stove of the class described, the combination with a burner bowl having a depending oil supply stem, a support, means coacting with the support and the stem to vary the height of the burner bowl, and means connecting the lower end of the stem with a source of oil supply comprising a conductor having a pair of bellows-diaphragms interposed therein to render the conductor flexible. 75

3. In a stove of the class described, the combination with a burner bowl having a depending oil supply stem, a support, means coacting with the support and the stem to vary the height of the burner bowl, means connecting the lower end of the stem with a source of oil supply comprising an outer conductor constructed so as to render it flexible, and an inner flexible member within said outer conductor and extending throughout the length thereof. 80

4. In a stove of the class described, the combination with a burner bowl having an upright oil supply stem, means for supporting the bowl in various positions of vertical adjustment, and a connection between the lower end of the stem and the source of oil supply comprising an outer flexible conductor and an inner flexible conductor, the outer conductor comprising a plurality of sections movable but non-slidable with reference to each other and the inner conductor comprising a plurality of sections movable and slidable with reference to each other. 95

5. In a stove of the class described, the combination with a burner bowl having a tubular supply stem, means for raising and lowering the bowl, and means for connecting said supply stem with a source of oil supply including a conductor having a bellows-diaphragm therein. 100

6. In a stove of the class described, the combination with a burner bowl having a tubular supply stem, of means for raising and lowering the burner bowl, and means for connecting the supply stem to a source of oil supply comprising a conductor having a plurality of diaphragm-like sections relatively arranged so as to render the conductor readily flexible. 110

7. In an oil stove of the class described, the combination with an oil supply pipe having a depending portion, of means permitting the removal of sediment from the pipe comprising a sump provided in said depending portion and having an opening in its 120

lower portion, and a plug adapted to be entered through said opening and having a screw-threaded engagement with the wall of the sump opposite the opening to normally close the opening.

8. The combination of a burner bowl having an upright tubular stem depending therefrom, a feed pipe spaced a substantial distance from the lower end of the stem, and
10 a connection between the feed pipe and the stem including a plurality of relatively movable but non-slidable members forming a flexible hollow member, and a flexible con-

ductor within said hollow member comprising a plurality of relatively slidable sections. 15

9. The combination of a burner having a burner bowl, a source of oil supply, and a connection between the source of supply and said bowl including a conductor comprising a plurality of hollow members having 20 flexible walls connected together at their centers so as to render the members relatively movable.

In testimony whereof, I have hereunto set my hand.

RUDOLPH HOFFMAN.
